REVOLVING DOOR HARDWARE

John W. Shields, Evansville, Ind., assignor, by
mesne assignments, to International Door
Company, Evansville, Ind., a corporation of
Illinois

Application November 3, 1934, Serial No. 751,367

10 Claims. (Cl. 20—18)

My invention relates broadly to revolving doors, and more particularly to a construction of stabilizing journal for revolving doors.

One of the objects of my invention is to provide a simplified construction of mounting means for revolving doors for facilitating installation and removal of the revolving doors.

Another object of my invention is to provide a construction of stabilizing journal for revolving doors having means for pivoting the revolving door structure on a stationary pintle, with means for retracting the pintle for facilitating installation or removal of the revolving door structure.

Still another object of my invention is to provide a simplified form of abutment for the inwardly directed peripheral edges of the revolving doors in a revolving door assembly.

A further object of my invention is to provide a retractile pintle for revolving doors having means for maintaining the pintle in either projected or retracted position.

A still further object of my invention is to provide a ball race mounting disposed within the tubular shaft structure of a revolving door for reducing frictional resistance and facilitating rotation of the door structure.

A further object of my invention is to provide a construction of spring actuated pintle for journaling a revolving door structure, in which a spring means is subjected to slight compression when the pintle is moved into position in a supporting bushing, and maintained under compression for yieldably maintaining said pintle in place and the revolving door in operative position.

Other and further objects of my invention reside in the construction of revolving door hardware and stabilizing journal, as set forth more fully in the following specification by reference to the accompanying drawings; in which:

Figure 1 is a side elevation, parts broken away and in section, of a revolving door provided with my improved detachable stabilizing journal; Fig. 2 is a sectional view on an enlarged scale, showing the relative position between the centrally disposed shaft, the tube rotating thereon, the plurality of sections of the tube cover, the hardware and the wings connected therewith; Fig. 3 is a sectional view on an enlarged scale of the stabilizing journal and its associated parts, the journal being relatively locked to its stationary step bearing embedded in the floor; Fig. 4 is a similar view with the journal shown in unlocked position and removed from the step bearing for the purpose of removing the door; Fig. 5 is a

side elevation of the centrally disposed tube; Fig. 6 is a sectional view taken on line 6—6 of Fig. 5, looking in the direction of the arrows; Fig. 7 is a horizontal section on an enlarged scale, taken on line 7—7 of Fig. 1; Fig. 8 is a detail horizontal section taken on line 8—8 of Fig. 3; Fig. 9 is a detail horizontal section taken on line 9—9 of Fig. 3; Fig. 10 is a transverse vertical section through the step bearing and a portion of the stabilizing journal, taken substantially on line 10—10 of Fig. 3; Fig. 11 is a side elevation partly in section, of the stabilizing journal; Fig. 12 is a side elevation with parts broken away and in section, disclosing one of the members used in association with my improved stabilizing journal; Fig. 13 is a detail top plan view of a portion of the step bearing; and Fig. 14 is a transverse vertical section taken on line 14—14 of Fig. 13.

Referring to the drawings in detail, reference characters 1 and 2 designate sleeve members disposed centrally of the vertically extending tubular shaft 10. The sleeve members 1 and 2 are interconnected by a coupling member 3 which is riveted within the sleeve members 1 and 2 by means of rivets 28. Sleeve member 2 is connected adjacent the upper portion thereof through the bolt member 21 having a circular head which is free to shift vertically and rotate within sleeve 2. Bolt member 21 passes through the upper end 30 of sleeve 2 but is confined therein within the limits defined by the depth of the sleeve and the abutment offered by the coupling member 3. A coil spring 23 is disposed concentrically about bolt 21 and located between the upper extremity of sleeve 2 and the lower face of slidable member 4. A rivet 29 extends through slidable member 4 and the upper end of bolt 21 for securing the bolt member 21 in rigid connection with respect to slidable member 4. The slidable member 4 has a 40 finger engaging member 5 connected therewith through bolt 19, as shown, and projecting laterally therefrom. In order that the hardware may be assembled readily, I provide a work aperture 36 in the tubular shaft 10 through which a screw 45 driver may be introduced in securing screw 19 in position in slidable member 4 for anchoring the finger engaging member 5 in position. The upper portion of the slidable member 4 has a laterally disposed recess 6 therein which receives the sleeve 50 32. Both the sleeve 32 and the finger engaging member 5 project through a longitudinally disposed slot 30 in the tubular shaft 10.

I provide a metallic shaft covering designated generally at 13 which is secured to tubular shaft 55

10 in any suitable manner such as by means of rivets 35. The construction of the metallic shaft covering 13 is illustrated more particularly in Figs. 8 and 9. The metallic shaft covering 13 is substantially in the form of a Geneva cross, that is to say, the metallic shaft covering 13 has four plane surfaces which substantially define elements of a rectangle interconnected by arcuate recessed portions which serve as longitudinally extending seats for the inwardly directed edges of the doors 42. The longitudinally extending arcuate shaped recesses form relatively tight seals with respect to the inwardly directed peripheral edges of doors 42. The metallic shaft covering 13 is so constructed adjacent the finger engaging member 5 that finger engaging member 5 projects through the slot 31 in covering 13. Slot 31 extends for a vertical distance slightly greater than the limits of movement of the finger engaging member 5. The covering 13 is apertured at 33 and 34 to receive the end of the detent 7. The detent 7 is shaped in the form of a reciprocatory plunger mounted in laterally extending sleeve 32 against the action of spring 22. As finger engaging member 5 is moved upwardly, detent 7 is retracted against the action of spring 22 and is thus withdrawn from aperture 34 and, when elevated to a position in alignment with aperture 33 is projected into aperture 33, as represented in Fig. 4 for maintaining the finger engaging member 5 and its associated parts, as hereinafter described, in elevated position.

It will be seen that the head bolt 21 is free to move rotatively within sleeve 2 and is also capable of limited translatory movement with respect to sleeve 2.

A somewhat different arrangement is provided in establishing a connection with sleeve member 1. The bolt member 20 has the circular head 40 thereof confined within sleeve 1 with the bolt member 20 free to rotate. A connection is provided between the lower end of bolt member 20 and the shaft 9. Shaft 9 is recessed at the upper extremity, as indicated at 9c and is laterally apertured at 9b. The end of bolt 20 fits into socket 9c and is pinned in position therein by means of rivet 27 which passes through the apertures 9b in the end of shaft 9 and through the lower extremity of bolt 20. A ball race comprising a pair of separable guides and a multiple arrangement of ball bearings is provided. This ball race and ball bearing unit constitutes a thrust bearing 24 which is located in a recess 1a in the lower extremity of the sleeve 1. The thrust bearing 24 provides an anti-friction means for supporting the thrust of spring 23 and allowing easy rotation of part 9. This spring pressure is continuously exerted to provide a means for holding part 8 into part 18. This action compensates for any 60 change in the bearing.

A pintle 8 is provided between the lower extremity of shaft 9 and a floor bearing. The pintle 8 has a frusto-conical end portion which projects into a frusto-conical seat 18a in the journal plate 18. The journal plate 18 is supported in a horizontal position in the bearing support 16 which is embedded in the floor structure designated generally at 45. Screw members 18c extend through apertures 18d in journal plate 18 and are secured in screw-threaded recesses 16a in bearing support 16. The journal plate 18 has a centrally depending portion through which the lateral aperture 18b extends, providing a mounting means for the laterally extending pin 26 75 which extends diametrically across the frusto-

conical seat 18a. The lower end of the pintle 8 is diametrically slotted, as shown at 8b by which pintle 8 is prevented from rotating. Pintle 8 is stationary and forms a support for stationary shaft 9 through the agency of the socket 8c in 5 the extremity of the pintle and the lateral apertures 8d therein through which rivet member 25 may be projected. For this purpose, shaft 9 is apertured at its lower extremity, as indicated at 9a and the said apertured portion aligned with 10 apertures 8d in socket 8c allowing rivet 25 to be passed therethrough for interlocking pintle 8 with shaft 9. The portion of pintle 8, shown at 8a, is shaped to receive the sleeve 17 which is supported at its lower periphery by means of shoulder 8e on pintle 8. The tubular shaft 10 is internally recessed at its lower end, as indicated at 10b. There is sufficient depth provided in the internal recess 10b at the lower end of the tubular shaft 10 to allow sleeve bearing 17 to be shifted upwardly as pintle 8 is retracted and disengaged from the laterally extending pin 26. The manner of retracting the pintle 8 is shown more clearly in Fig. 4. By reason of the journal mounting of tubular shaft 10 on sleeve bearing 17 at the 25 bottom of the door, extreme precision in operation of the revolving door may be maintained.

In order to provide for the support of revolving doors 42 by the vertically extending tubular shaft 10, I provide key-ways 37 and 38 30 in the tubular shaft 10, as shown more particularly in Figs. 5 and 6. Key-ways 37 and 38 are located adjacent the opposite end of tubular shaft 10 therein, each adapted to receive keys 39 which interlock the revolving door hardware 35 shown generally at 40 with the tubular shaft 10. The revolving door hardware 40 carries the hangers 41 which support the doors 42 in the general arrangement shown in Figs. 1 and 2.

It will be observed that the spring 23 is at all 40 times under slight compression. Pintle 8 is projected downwardly, by movement of finger engaging member 5, to the position shown in Fig. 3, (Page 6). When the finger engaging member 5 is actuated by a vertical upward movement 45 for the purpose of retracting pintle 8, spring 23 is maintained under slight compression by reason of the narrow limits of movement afforded to the head of bolt 21 between the upper end of sleeve 2 and the abutment established by coupling member 3. The installation or the removal of the revolving door becomes an extremely simple matter when using the stabilizing journal of my invention as a minimum number 50 of operations to collapse the doors and shift the 55 doors into or out of position are necessary. The rotation afforded by the shaft 9 interconnecting bolt 20 and sleeve member 1, and the rotation permitted by the sleeve 2 and bolt member 21 is sufficient to insure rotation of the revolving doors 60 with a high degree of precision and balance.

I have found the revolving door hardware of my invention highly practical in its construction. While I have described my invention in one of its preferred embodiments, I realize that 65 modifications may be made and, accordingly, I intend no limitations upon my invention other than may be imposed by the scope of the appended claims.

What I claim as new and desire to secure by 70 Letters Patent of the United States is as follows:

1. Revolving door hardware comprising a vertically disposed tubular shaft, means carried by said shaft for supporting revolving doors with respect thereto, a casing member secured to said 75

tubular shaft, said casing member having vertically disposed recesses therein for providing a sealed connection with the inwardly extending edges of the revolving doors, a central member within said tubular shaft, said central member including a pintle and an operating portion, means disposed between said pintle and said operating portion whereby said pintle is rotatable with respect to said tubular shaft, and means for shifting said operating portion for effecting a projection or a retraction of said pintle.

2. Revolving door hardware comprising a vertically disposed tubular shaft, means carried by said shaft for supporting revolving doors with respect thereto, a casing member secured to said tubular shaft, said casing member having vertically disposed recesses therein for providing a sealed connection with the inwardly extending edges of the revolving doors, a central member within said tubular shaft, said central member including a pintle and an operating portion, means disposed between said pintle and said operating portion whereby said pintle is rotatable with respect to said tubular shaft, and means connected with said operating portion and extending through said tubular shaft and said casing member for effecting a raising or lowering of said pintle for retracting said pintle to a position within said tubular shaft or projecting said pintle to a position beyond the end of said tubular shaft.

3. Revolving door hardware comprising a vertically disposed tubular shaft, revolving door hangers carried by said shaft, revolving doors supported by said hangers, a casing member secured to said tubular shaft, said casing member having longitudinally extending recesses therein providing seats for the inwardly extending edges of the revolving doors, said tubular shaft and said casing member having aligned slots therein, a central actuating member disposed within said tubular shaft, a finger engaging member connected with said central actuating member and projecting through the aligned slots in said tubular shaft and said casing member, a pintle connected with said central actuating member and adapted to be projected from or retracted into said tubular shaft under control of said finger engaging member, and means disposed between said pintle and said central actuating member whereby said pintle is rotatable with respect to said tubular shaft.

4. Revolving door hardware comprising a vertically disposed tubular shaft, revolving door hangers carried by said shaft, revolving doors supported by said hangers, a casing member secured to said tubular shaft, said casing member having longitudinally extending recesses therein providing seats for the inwardly extending edges of the revolving doors, said tubular shaft and said casing member having aligned slots therein, a central actuating member disposed within said tubular shaft, a finger engaging member connected with said central actuating member and projecting through the aligned slots in said tubular shaft and said casing member, a pintle connected with said central actuating member and adapted to be projected from or retracted into said tubular shaft under control of said finger engaging member, and latching means carried by said central actuating member and engageable with said casing member for latching said pintle in either retracted or projected position, and means disposed between said

pintle and said central actuating member whereby said pintle is rotatable with respect to said tubular shaft.

5. A revolving door hardware comprising a vertically disposed tubular shaft, means for journaling said shaft, hangers carried by said shaft for supporting revolving doors with respect thereto, and a casing member carried by said shaft and coextensive with the exposed portion thereof, said casing member having a cross-section substantially in the shape of a Geneva cross and providing circular sealing zones for the inwardly directed peripheral edges of the revolving doors.

6. A stabilizing journal for revolving doors comprising in combination with a tubular shaft carrying the door wings, a pintle mounted in the lower end of said shaft and provided with means on the lower end thereof for non-rotatively engaging a socket in the floor structure, a link member rotatively mounted with respect to said pintle, an actuating member reciprocally mounted in said tubular shaft and rotatable therewith, a bolt member fixed in said actuating member and slidably mounted in said link member, spring means mounted on said bolt member, said spring means operative when said pintle is engaged in said socket to maintain said pintle in position.

7. A stabilizing journal for revolving doors comprising in combination with a tubular shaft carrying door wings, a pintle mounted in the lower end of said shaft, a bearing member disposed between said pintle and said shaft, said pintle having a slot in the lower end thereof for engaging a bar set in a socket in the floor structure whereby said pintle is held non-rotative, a link member rotatably mounted with respect to said pintle, an anti-friction bearing disposed between said link member and said pintle, an actuating member mounted in said shaft and rotatable therewith, said actuating member resiliently connected with said link member; said pintle, said link member and said actuating member being reciprocally mounted in said tubular shaft, said shaft being rotatable about said pintle.

8. Revolving door hardware comprising a vertically disposed tubular shaft, means for supporting door wings on said shaft, an actuating member longitudinally slidably within said tubular shaft, a pintle slidably and rotatably mounted in the lower end of said tubular shaft, and a link member disposed in said tubular shaft, said link member being rotatably connected with said pintle and resiliently connected with said actuating member, whereby said pintle may be resiliently projected from and drawn into said tubular shaft.

9. A stabilizing journal for a revolving shaft comprising in combination with a revolving tubular shaft, an actuating member longitudinally slidably within said tubular shaft, a pintle slidably and rotatably mounted in the end of said tubular shaft, a link member disposed in said tubular shaft and rotatably connected with said pintle and resiliently connected with said actuating member, whereby said pintle may be resiliently projected from and drawn into said tubular shaft, said tubular shaft having a fixed socket disposed adjacent the end thereof and engageable by said pintle in its projected position.

10. Revolving door hardware comprising a vertically disposed tubular shaft, a pintle rotatably and slidably mounted in the lower end of said

tubular shaft, an actuating member longitudinally slidable within said tubular shaft, a link member disposed in said tubular shaft intermediate said pintle and said actuating member and 5 respectively connected therewith, a coil spring disposed between said link member and said actuating member, and an anti-friction device dis-

posed in the connection between said link member and said pintle, whereby said pintle is rotative with respect to said link member and said actuating member, and said pintle and said link member are resiliently connected with said actuating member. 5

JOHN W. SHIELDS.
